U.S. Cl. D33—30

Fig. 1.

Fig. 3.

Fig. 2.

Fig. 4.

Fig. 5.

FIG. 1 is a side elevational view of the dispenser for toilet articles embodying my new design, the other side is a mirror image of the side shown;

FIG. 2 is a front, elevational enlarged view of the dispenser shown in FIG. 1;

FIG. 3 is a rear elevational view of the dispenser shown in FIG. 2;

FIG. 4 is a bottom plan view of the dispenser without the holding bracket; and

FIG. 5 is a fragmentary, enlarged, top, perspective view of the dispenser as seen in FIG. 3.

The bracket shown in FIGS. 1 and 2 is for illustrative purposes only.

I claim:

The ornamental design for a dispenser for toilet articles, as shown and described.
